UNITED STATES PATENT OFFICE

MIKLÓS HAIDEKKER, OF BUDAPEST, HUNGARY

WIRe FENCE MAKING MACHINE

Application filed September 26, 1929, Serial No. 395,408, and in Hungary October 1, 1928.

This invention relates to a machine for producing wire fencing consisting of straight or undulated stays and strands comprising a pair of wires twisted together. The operation of this machine is based on the principle of conducting the pairs of wires for the strands through a twister which will hold the same in spaced relation to one another, these wires thereby forming a shed in front of the twisters. Upon the insertion of a stay into the shed and forwarding the same into the corner of the shed the wires of the strands are twisted together behind the stay. Fencing machines of this kind are described in U. S. Patent No. 783,832, filed Oct. 8, 1903. The present invention relates to certain improvements in the construction of these known machines resulting in a considerable simplification of the machine, in decreasing its power consumption and making it possible to produce a closer meshed wire netting, the strands of which are considerably nearer to each other than those of the fencing produced with the known machines.

In order to produce a neat fencing it is necessary to stop the twisting of the wires forming the strands by means of a knife edge arranged at right angles to the strands. This knife edge in the known machines was provided on a flat iron rod or tongue movably mounted in the interior of each of the twisters and guided in longitudinal slots therein. In its foremost position this tongue served to stop the twisting of the wires of the strands while in its rearmost position it enabled the stays to be introduced into the shed. In order to avoid the use of these cumbersome tongues, which occupied a considerable space and had to be permanently actuated during the operation of the machine, the knife edges for stopping the twisting of the wires of the strands are provided on a member rigidly mounted on the twister in such a manner as to leave an open space for the introduction of the stays. The edges for limiting the twisting of the wires are arranged at such a distance from the twister at which it is desired or necessary to limit such twisting. The knife edges are preferably provided on resilient tongues fastened for instance to the

front surface of the twisters. When the stay is moved from the place of introduction into the corner of the shed these tongues are resiliently yielding to the stay and do not restrict the free movement thereof. The fact that the member carrying the limiting edges consists of a small plate only, secured to the front of the twister and substitutes the tongue guided in the interior of the twister, makes it possible materially to reduce the diameter of the same and to provide twisters of considerably smaller wall thickness than heretofore, this circumstance enabling the twisters to be arranged closer to each other and thereby providing the possibility of the manufacture of a wire netting of the character described of much closer mesh than it was possible up till now to produce.

The wire fencing machine according to the present invention is provided with improved twister having a front and a rear head portion each of which is provided with notched rollers for the smooth passage of the strand wires and for holding such strand wires in spaced relation so as to form a front and a rear shed. The front shed is formed for the purpose of introducing the stays while the rear shed is formed as an inevitable consequence of the twisting of the wires, the said rear shed allowing a smooth passage or introduction of the wires of the warps or strands into the twisters at the rear end thereof.

Another feature of the invention is the arrangement of an improved device for guiding and forwarding the stays into the corner of the shed. According to the present invention for performing these two operations one single device is used only, consisting of guiding cones parted in the longitudinal direction and arranged between the twist limiting devices and in front of the twisters. This device is opened by the stays and is automatically closed after the same have left.

This arrangement, besides simplifying the construction of the machine also helps to enable the twisters to be arranged closer to each other.

In the accompanying drawings several forms of the machine according to the invention are shown by way of example.

Fig. 1 is a side view and

Fig. 2 is a plan view of the machine.

Fig. 3 shows part of one of the twisters in longitudinal sectional view, on an enlarged scale.

5 Fig. 4 is a front view of a special type of twister.

Fig. 5 shows a modified form of the twister in top view.

10 Fig. 6 is a cross sectional view taken on line VI—VI of Fig. 3.

Fig. 7 is a side view of the guide for the stays and

15 Fig. 8 is the top view thereof, partly in section.

Fig. 9 is a side view of a modified form of the stay-guide and

Fig. 10 is a front view thereof.

20 Fig. 11 is a perspective view of another form of the stay-guide.

25 A twister comprises two twisting jaws, a front jaw 6 and a rear jaw 7. These jaws are interconnected by means of a shaft 1 which is journaled in the bearings 3. For rotating the twisters the shaft 1 is provided with a helicoidal gear 4 meshing with a helicoidal gear 5 on the shafts 45 by which means the twisters are driven. In the form shown the helicoidal gears 4 on adjacent twisters are 30 arranged in spaced relation to each other, this arrangement providing the possibility of placing the twisters closer together than it would be possible were the gears 4 arranged at corresponding points intermediate the 35 length of each of the twisters.

The jaws of the twisters are formed by two lateral members 8 and 9 of which member 8 may be made integral with the shaft 1 while member 9 is made of a separate piece of metal

40 in order to facilitate the assembling of the twister and is rigidly connected to member 8 by rivets or screws 14 and 15. Journaled between the lateral members of the jaws there are rollers 10 and 11 for guiding the warps.

45 The rollers 11 are provided with a circumferential groove deeper than the groove in the rollers 10 in order to prevent the gliding off of the warps.

50 In order to provide for producing a wire netting as close meshed as possible, the dimensions of the twisters are to be reduced as far as possible. For this purpose the rollers 10 and 11 are made integral with their spindles this making it possible to choose 55 rollers of smaller diameter than those which are provided with a hole to run on a fixed axle.

59 Between the two lateral members 8 and 9 there is arranged a spacer member 16 which holds the said lateral members apart and prevents the rollers from being jammed therebetween. The spacer member 16 is made in the form of a wedge the converging faces of which guide the warps when the 65 same are introduced into the twister.

For the passage of the warps to the front jaw the shaft 1 is provided with an axial bore 21 into which is inserted a piece of strip metal 19 dividing the bore 21 so as to form two separate ducts, one for each of the warps 70 26 passing through the shaft to the front jaw, this facilitating to a great extent the introduction of the warps into the twister. The two extremities of the strip 19 dwell in recesses formed in the spacer members 16 75 whereby the said members are secured against turning in the jaws. Preferably, the strip 19 is somewhat narrower than the bore 21 (Fig. 6) so that it may resiliently yield to a knot of wire passing through one of the ducts 80 in the bore.

Secured to the front surface of the twisters there are spring members 22 for limiting the twisting together of the warps. The limitation of the twisting is performed by the edges 85 24 of the two convergently protruding elastic blades 23 which are situated within the shed formed by the two warps 26, the stays entering the shed at about the inner extremities of the forwardly converging blades, where they are situated most widely apart, so that these blades do not interfere with the introduction of the stays. In consequence of the resilient characteristics of the blades 23 these blades readily evade to the stays when the same leave between the two edges 24 to be pushed into the corner of the shed. The two edges 24 may normally be situated somewhat apart (Fig. 3) but are pressed together at the twisting of the two warps to be again released when the finished netting passes away thus allowing the next stay to leave between the edges when the stay is pushed into the corner of the shed.

95 According to the present invention for guiding the stays when shooting the same into the shed and for pushing the stay thus introduced into the corner of the shed one and the same device is utilized.

100 For this purpose there are arranged between the twist limiting members 22 to 24 guiding members for the stays fastened to the slide 2 (Fig. 7). Upon the introduction of the stay 25 the slide 2 is pushed forward by the action of the machine and with this movement the stay is pushed into the corner of the shed.

105 In the form shown in Figs. 7 and 8 the guide for the stay 25 comprises a stationary conical member 12 and a movable conical member 13. In their closed position shown 110 in Fig. 7 in full lines these two members form a cylindrical cavity 27 to which is attached a conical surface 28. The conical surface 28 opens toward the direction from which the stay is introduced, indicated in Fig. 8 by the arrow 43 (see the member in the center in Fig. 8 which is a sectional view taken on line A—B of Fig. 7), so that the stay may not leave the direction in which it 115 120 125 130

is introduced. The stationary conical member is fastened to an upright 17 secured to the slide 2. At its upper extremity the upright ends in two ears 18 (see the upper stay-guide member in Fig. 8, which is a sectional view taken on line C—D of Fig. 7) in the bore 20 of which a spindle 44 is secured on which is journalled the ear 30 of the movable conical member 13. The movable conical member 13 may be swung round the spindle 44 and may therefore be moved into the position shown in Fig. 7 in dotted lines.

In the form of the guide for the stays shown in Figs. 9 and 10 the same comprises two spring members 31 and 32 fastened to the upright 17. For forming a guiding cone the spring members 31 and 32 are obliquely bent outwards, so that the outwardly bent portions 33 and 34 together with the upright 17 form a three edged truncated pyramid which constitutes the cone proper for guiding the stays. The free edges 35 of the spring members are touching each other in order to close up the cone. In order that the stay may securely be deflected into the cone even if it strikes the upright 17 that portion of the latter which is situated between the spring members 33 and 34 is bevelled at 36, (see Fig. 9).

In the form shown in Fig. 11 the guiding cone is formed of a single piece of resilient sheet metal folded into the form of a three edged prism. The back portion of this guiding cone is secured to the upright 17 for which purpose it is provided with holes 38 to admit screws. From the upper edge of the back portion 37 a blade 39 is bent downwards and from the lower edge of said back portion the blade 40 is bent upwards, the edges 41 of said blades touching each other to close up the cone. In order that a laterally evading stay may securely be deflected into the cone the edges 42 of the blades 37, 39 and 40 lying on that side of the cone at which the stay enters, are bent outwardly in a trumpet-like fashion.

As soon as the stay has been shot through the whole of the width of the wire netting through all the guiding cones and twist limiting members a correct length of stay wire is cut off the reel and this cut off portion of wire, which is the one inserted into the cones and the twist limiting members, is pushed forward by means of the uprights 17 and the guiding cones in the direction of the arrow 29, the stay being thereby pressed into the corner of the shed and leaving the twist limiting members 22, 23. If the thickness of the stay wire, or the height of its waves is greater than the distance of the edges 24 the latter will resiliently yield to the stay. The shafts 1 of the twisters are now rotated whereby the strands or warps are twisted together. The twisting together of the warps is limited by the edges 24 which are pressed against each

other by the strands lying on the blades 23, the same thereby acting as a single edge.

At the twisting together of the warps the same are also twisted together behind the rear jaws 7, a second or rear shed being thereby formed by the warps behind the jaws 7. It is such rear shed that makes it possible to pull the warps forward when the finished netting is rolled upon the wind-up drum provided for this purpose. This wind-up drum is described, together with the other parts of the machine not described or illustrated in this specification, in the said U. S. Patent No. 783,832.

By this time the slide 2 together with the guiding cones returns to its rear position. At the returning of the guiding cones the stay 25 just pushed into the corner of the shed must naturally remain in that position and as a necessity must depart from the guiding cones. In the form shown in Figs. 7 and 8 this is effected through the swinging of the movable cone member 13 into the position shown in dotted lines in Fig. 7. In the forms shown in Figs. 9 and 10 the opening of the guiding cones is effected by the edges 35 of the resilient blades 31 and 32, or 33 and 34 moving away from each other. In the form shown in Fig. 11 the edges 41 are resiliently opened in the same manner as in the form according to Figs. 9 and 10. The opening of the guiding cones is effected by the stay at the relative movement of stay and the slide 2. In the form shown in Figs. 7 and 8 the movable cone member is shut by gravity.

In the form of the twisters shown in Figs. 1 to 3 the twisting together of the warps is limited by the edges 24 of the resilient blades 23, such edges being in the form of straight lines. The limiting edges may, however, also be made bow shaped, such bow being situated either in a horizontal, (Fig. 5) or in a vertical plane (Fig. 4) as viewed in the shed forming position of the twisters. This form of the limiting edges provides a greater security against the slipping off of the warps from the blades 23.

In the forms of the twisters above described each twister is provided with two edges 24. It should be noted however, that a single edge may be utilized as well and this may be provided either on an upper or on a lower blade 23.

Of the numerous modifications which may possibly be made within the scope of the appended claims it should be mentioned that the twisting jaws 6 and 7 may also be made of a single piece in which case the pins for journalling the rollers 10 and 11 are inserted from outside through bores in the jaws and in the rollers. The edges 24 for limiting the twisting together of the warps may also be arranged on rigid (non elastic) blades if the movability of the edges is assured by a pivotal arrangement of the rigid blades. The essen-

tial feature of the twist limiting members according to the invention is only this that the limiting edges should be secured to the twisters in such a manner as to clear the space necessary for the stays to be inserted into the shed.

Having now particularly described my invention, I declare that what I claim is:

- 10 1. In a machine of the character described, rotatable twisters receiving the warp wires, means for guiding the warp wires arranged on the twisters, twist limiting members secured to said twisters within the shed formed by said wires adapted to clear the space necessary for the stay to be inserted into said shed, said twist limiting members having twist limiting edges.
- 15 2. A machine as claimed in claim 1 having resilient twist limiting members.
- 20 3. A machine as claimed in claim 1 having curved twist limiting edges.
- 25 4. In a machine of the character described, rotatable twisters having front and rear jaws for receiving the pairs of wires and forming a front and rear shed respectively, a shaft for connecting the said jaws having a longitudinal bore, gear wheels on the said shaft for driving the twisters, the said gear wheels being arranged in spaced relation on consecutive shafts and twist limiting members secured to said twisters within the front shed formed by said wires adapted to clear the space necessary for the stays to be inserted into said shed, said twist limiting members 30 having twist limiting edges.
- 35 5. In a machine of the character described, rotatable twisters having front and rear jaws for receiving the pairs of wires and forming a front and rear shed respectively, the said jaws being made of two pieces secured to one another, guiding rollers for the warps made integral with their axles and rotatably mounted between said jaw members, a shaft for connecting the said jaws having a longitudinal bore and twist limiting members secured to said twisters within the front shed formed by said wires adapted to clear the space necessary for the stays to be inserted into said shed, said twist limiting members 40 having twist limiting edges.
- 45 6. A machine as claimed in claim 5 having a spacer member between the two pieces of the jaws.
- 50 7. A machine as claimed in claim 5 having a metal strip mounted in the bore of the shaft connecting the jaws, said strip subdividing the bore into two ducts.
- 55 8. A machine as claimed in claim 5 having a metal strip mounted in the bore of the shaft connecting the jaws, said strip being narrower than the diameter of the bore and subdividing the bore into two ducts.
- 60 9. In a machine of the character described, rotatable twisters receiving the pairs of wires and guiding cones for guiding the stays said

guiding cones consisting of blade springs and being secured to the slide of the machine adapted to push the stay into the corner of the shed.

10 10. In a machine of the character described, rotatable twisters for receiving the pairs of wires and guiding cones for guiding the stays said guiding cones consisting of an upright secured to the slide of the machine adapted to push the stay into the corner of the shed, and two blade springs secured to said upright.

15 11. In a machine of the character described, rotatable twisters for receiving the pairs of wires and guiding cones for guiding the stays said guiding cones consisting of an upright secured to the slide of the machine adapted to push the stay into the corner of the shed and two blade springs secured to said upright, the said blade springs forming a truncated pyramid with the said upright, and the said upright being bevelled between the said springs.

20 In testimony whereof I have affixed my signature.
